(57) **CLAIM**

The ornamental design for a display table, as shown and described.

DESCRIPTION

FIG. 1 is a front perspective view of a display table showing a first embodiment of our new design;

FIG. 2 is a front view thereof, the rear view being a mirror image of the front view;

FIG. 3 is a right side view thereof, the left side view being a mirror image of the right side view; and

FIG. 4 is a top view thereof.

FIG. 5 is a front perspective view of the display table of FIG. 1 with a portion of the unclaimed subject matter removed for clarity;

FIG. 6 is a front view thereof, the rear view being a mirror image of the front view;

FIG. 7 is a right side view thereof, the left side view being a mirror image of the right side view; and

FIG. 8 is a top view thereof.

FIG. 9 is a front perspective view of a display table showing a second embodiment of our new design;

FIG. 10 is a front view thereof, the rear view being a mirror image of the front view;

FIG. 11 is a right side view thereof, the left side view being a mirror image of the right side view; and

FIG. 12 is a top view thereof.

FIG. 13 is a front perspective view of the display table of FIG. 9 with a portion of the unclaimed subject matter removed for clarity;

FIG. 14 is a front view thereof, the rear view being a mirror image of the front view;

FIG. 15 is a right side view thereof, the left side view being a mirror image of the right side view; and,

FIG. 16 is a top view thereof.

The features shown in broken lines are portions of the display table or environmental subject matter to the display table forming no part of the claimed design. The features shown in long dash-short dash bolded broken lines indicate the bounds of the claimed design and otherwise form no part of the claimed design.
